STRIP CASTING MACHINE

Harry L. Horn, Dallas, Tex.

Application September 7, 1948, Serial No. 48,116

7 Claims. (Cl. 22—57.2)

1

This invention relates to new and useful improvements in strip casting machines for making printer's slugs, leads and rules, and more particularly to machines of the general type shown in the United States Letters Patent, No. 1,438,951, granted to Benjamin S. Elrod on December 19, 1922, and No. 1,800,938, granted to Arthur A. Hedley on April 14, 1931, the machines being constructed and arranged to form a continuous strip of type metal which is then cut into sections of desired lengths.

The invention, therefore, relates broadly to the art of die-expressing and drawing of metal, and more particularly to the forming of continuous strips or bars of metal from a molten body thereof. Machines used for practicing the aforesaid method or art are adapted to form a continuous metal strip by drawing the same from the bottom or from below the surface of a molten body of the metal, the metal being drawn through the shaped channel of a suitable die and cooled in passing through said channel, so that the metal enters one end of the channel as a fluid and emerges from the other end thereof as a solid strip. The movement of the strip is effected by pulling upon the solidified portion thereof protruding from the die, the molten metal being subjected merely to sufficient pressure to cause it to follow through the die channel rather than to a pressure great enough to directly expel or extrude the metal through the die channel. After the metal bar or strip has been formed in sufficient length, it is cut off in sections of predetermined dimension and deposited upon a suitable stacking table or surface from which the severed strips are removed for storage or use.

In the devices of Elrod and Hedley, hereinbefore mentioned, the die channel member is bolted to an outlet neck formed on the pot or crucible containing the molten type metal and the cooling mechanism for the die is incorporated as an integral part of the assembly, or the die or mold is set in an outlet throat or opening from the pot or crucible containing the molten metal and is held in place therein by means of a portion of the metal contained in the pot or crucible throat which has been permitted to harden or set around the die between the die and the wall of the throat. Furthermore, in both of the foregoing devices, the configuration of the metal strip formed by the die is fixed and unchangeable, it being necessary to replace the die with another having the desired configuration when it is desired to produce a strip having a different shape, size or printing face thereon. Also, the cooling mechanism of both previous devices is an integral part of either the

2

die or the throat of the crucible in which the die is secured and cannot be readily repaired, adjusted or replaced without completely shutting down the entire machine for long periods of time and completely replacing the cooling mechanism and occasionally rebuilding both the crucible and the cooling mechanism. Also, the position of the die in the foregoing devices is positively fixed after it is set in place and cannot be changed or moved to correct bowing or other misalignment of the strip of type metal formed by the die.

In the Elrod machine presently in use, the strip of metal formed by the die is formed in a vertical position with the printing face downwardly so as to ride or drag on any surface over which it passes. Furthermore, the pulling means for drawing the strip from the die channel alternately grips and releases the strip of metal, and the strip must be held by a brake or holding means while the pulling means is moved toward the die for a new grip to further draw the strip from the die channel. Also, the strip of metal severed from the continuous strip being drawn through the die is permitted to fall on the surface of the stacking table with the printing edge of the strip resting upon or contacting such surface, whereby the printing face is easily deformed, or roughened and damaged.

It is, therefore, one object of this invention to provide improved machine for producing printer's leads, slugs and rules rapidly and automatically after being initially started and adjusted.

An important object of the invention is to provide a strip casting machine having an improved mold or die for forming the strip, improved drawing and holding means, and an improved cut-off and stacking mechanism.

Another object of the invention is to provide in a strip casting machine an improved mechanism for drawing the strip of formed metal through the mold or die, which pulling mechanism continuously grips the formed strip and holds the same, said mechanism being intermittently moved to cause the strip to be drawn through the die.

A particular object of the invention is to provide a strip casting machine, of the character described, wherein the strip of metal formed by the machine is delivered from the channel of the die in a horizontal position, whereby the printing edge of the strip is protected against dragging on the surface of the machine or against contact with moving parts thereof, said formed strip being severed into sections of desired length and deposited upon the stacking table with the printing face uppermost to assure protection

of the printing face of the severed sections of the strip.

It is a further object of the invention to provide an improved severing and stacking mechanism for cutting the strip into sections of desired length and stacking the same with the printing face upward to prevent damage to such printing face.

A still further object of the invention is to provide in a strip casting machine of the character set forth, an improved lubricating mechanism for injecting or admitting lubricants to the strip forming channel of the die of the machine for reducing frictional adherence of the formed strips to the wall of the die and facilitating the drawing of the formed metal through the die.

Another particularly important object of the invention is to provide in a machine of the character described means for controlling and maintaining the temperature of the metal passing through the die channel at the proper temperature to prevent the formation of pits or irregularities in the printing face of the strip formed by the die, such means including an auxiliary heater directed at and heating the printing edge side of the mold or die.

Another object of the invention is to provide a strip casting machine wherein all operating parts of the machine are quickly and readily detachable and replaceable, whereby such parts may be adjusted, removed and repaired or replaced without shutting down the machine for long periods of time or requiring the complete rebuilding of certain parts of the machine.

Additional objects and advantages of the invention will readily be apparent from the reading of the following description of a device constructed in accordance with the invention, and reference to the accompanying drawings thereof, wherein:

Figure 1 is a front elevation of a strip casting machine constructed in accordance with the invention.

Figure 2 is a plan view of the device in Figure 1.

Figure 3 is a longitudinal vertical sectional view taken on the line 3—3 of Figure 2.

Figure 4 is an enlarged transverse vertical sectional view taken through the oiling mechanism of the machine.

Figure 5 is enlarged longitudinal vertical sectional view of the lower portion of the lubricating mechanism and one end of the strip forming die,

Figure 6 is an enlarged longitudinal vertical sectional view taken through the pulling mechanism of the machine.

Figure 7 is a transverse vertical sectional view taken on the line 7—7 of Figure 6.

Figure 8 is a vertical cross-sectional view taken on the line 8—8 of Figure 7.

Figure 9 is a longitudinal vertical sectional view of the cut-off and stacking mechanism, and

Figure 10 is a transverse vertical sectional view taken on the line 10—10 of Figure 9.

In the drawings, the numeral 15 designates a bench or table-top of a strip casting machine used for forming continuous strips or bars of metal from a molten body thereof in the form of printer's lead, slugs, rules, and the like, said tabletop being supported upon legs 16 and having a peripheral skirt 17 surrounding the legs below the tabletop and enclosing the drive mechanism to prevent accidental contact with such moving parts by the operator of the machine.

Mounted on the tabletop 15 is a melting pot or crucible 18, substantially cylindrical in form, and beneath the crucible is mounted a gas burner or other heating element 19 to which fuel is supplied for heating the crucible for melting the type metal, lead, or similar soft metal alloys capable of fusion at moderate temperatures and having a fair degree of tensile strength when cold, which metals are used in forming the strip. The admission of fuel to the burner is controlled by a valve having a handle 20 accessible on the front skirt 17 of the machine.

The crucible is provided with an outlet passage or spout 21 communicating with the lower portion of the crucible and extending laterally therefrom. The inner end of the passage or spout communicates with the lower end of a pump cylinder 22 which is disposed in the body of the crucible and forms an integral part of the lower portion or bottom thereof. A piston or plunger 23 is slideable within the cylinder and is actuated by means of a connecting rod 24 extending upwardly from the piston and connected to one end of a lever 25 which is fulcrumed between lugs 26 formed on the upper end of the crucible body. The lever 25 is actuated by means of a push rod 27 which is connected with the outer end thereof and extends downwardly below the tabletop. A cam rider finger 28 is adjustably mounted on the lower portion of the push rod and is engaged by a cam 29 carried by the main drive shaft 30 of the machine and rotated thereby. Rotation of the cam member by the drive shaft causes the cam member to engage the rider finger 28 and cause reciprocating movement of the push rod, thus likewise causing reciprocating movement of the piston 23 in the cylinder 22.

The push rod 27 is constantly urged upwardly by a coiled helical spring 31 which surrounds the rod above the tabletop 15 and is adjustably connected with said rod by means of a nut 32 threaded on the rod. The spring constantly urges the rod upwardly to urge the piston 23 downwardly in the cylinder 22. In its reciprocating movement, the piston 23 is lifted until it is positioned above a lateral opening 33 in the side wall of the cylinder, whereby molten metal may enter through said opening into the bore of the cylinder, whereupon downward movement of the piston will force the metal outwardly along the passage of the spout 21 to form a strip S of solidified metal in a manner which will be hereinafter described.

A rotatable ported cylindrical plug valve 34 is mounted in the spout passage 21 for controlling flow of molten metal through the passage of the spout. A valve stem 34' extends upwardly from the valve plug to a point above the upper end of the crucible and is provided with a handle 35 for manipulation by the user of the device.

Also communicating with the passage of the lateral spout 21 from the crucible is an oil feeding mechanism 36, which may be of any suitable desired type, for feeding oil to the molten metal within the passage of the throat for reducing the resistance to the drawing of the formed strip of solidified metal, as will hereinafter be more fully explained. The lubricating mechanism includes a cup or container 37 having an elongate cylindrical tube or conductor 38 extending axially downward from its lower end and containing a bore 39. The portion of the tube adjacent the bottom of the cup is enlarged in diameter and 75 provided with external screw threads 40, whereby

the tube may be inserted into and secured in an opening 41 in the housing 42 for the outlet throat from the crucible and extend downwardly therethrough into the throat passage, as clearly shown in Figures 4 and 5. A cap 42 is removably secured to the upper end of the cup 37 by screws 43 and is provided with an axial opening 44 through which an elongate valve rod 45 extends. The valve rod likewise extends downwardly through the bore of the tube 38 and is arranged to engage an upwardly facing seat 47 in a valve body 48 removably connected to the lower end of the tube. The valve plunger or rod 45 is normally urged downwardly into engagement with the seat by means of a spring 49 which is confined between the cap 42 and a flange washer 50 secured to the valve rod and normally spaced from the bottom of the cup 37, as clearly shown in Figure 4. The lower end of the valve body 48 extends into the throat passage 21, whereby lubricant from the cup 37 will pass through the bore 39 of the tube 38 and past the valve seat 47 through a restricted passage 51 in the valve body to the throat passage 21, for lubricating the molten metal passing therethrough. A downwardly facing valve seat 52 is formed in the lower end of the valve body and is arranged to be engaged by a float valve plug 53 for preventing back-flow of oil or molten metal into the bore of the tube thereabove. A cross pin 54 is provided at the lower end of the valve body for supporting the plug 53 in its lowermost position.

The valve plunger rod 45 is lifted out of engagement with the upwardly facing seat 47 by an elongate L-shaped lift rod 55, having a bifurcated end 56 which engages beneath a nut 57 threaded on the upper end of the plunger rod. The elongate vertical portion of the lift rod extends downwardly through an opening in a guide plate 58 secured by means of bolts 59 to the upper end of the spout housing, and then extends downwardly through an opening in the tabletop 15. A roller wheel 60 is mounted on a transverse pin 61 at the lower end of the lift rod and is positioned to be engaged by a cam pin 62 carried by a rotatable follower disc 63 forming a part of a Geneva movement mechanism.

The follower disc is provided with plurality of uniformly spaced notches 64 in its periphery, and between the notches the periphery of the disc is formed with concave sections 65, which engage and ride upon the circular surface 66 of the actuating disc 67 of the Geneva movement. The actuating disc is provided with an annular flange 68 on one side, and an actuating pin 69 is carried by the flange and is adapted to engage in the notches 64 of the follower disc to cause the follower disc to be turned through a predetermined number of degrees. The circular surface 66 of the actuating disc is cut away adjacent the pin 69 to permit the points on each side of the notches in the follower disc to pass when the pin is engaged in one of the notches, so that the next adjacent concave surface 65 is turned into contact with the circular surface 66 of the actuating disc. Manifestly, the actuating disc must be turned through a predetermined number of revolutions to cause a single revolution of the follower disc. For each single revolution of the follower disc, the cam pin 62 engages the roller wheel 60 at the lower end of the lift rod to elevate the lift rod and thus lift the valve plunger 45 to open the passage through

the valve body 48 and permit oil to pass into the throat passage 21 to lubricate the metal therein.

The actuating disc 67 is mounted on the main drive shaft 30 of the machine and is turned thereby. The follower disc is mounted on a parallel stub shaft 70, spaced from the main shaft and carried by suitable depending journal members 71 mounted on the underside of the tabletop.

It is preferable that the movement of the lift rod which elevates the valve plunger to permit lubricant from the cup 37 to flow into the throat passage be so timed with respect to the movement of the piston 22 of the molten metal pump in the crucible that the valve plunger will be elevated for only a short portion of the time during which the piston is moving upwardly to draw molten metal from the crucible into the pump cylinder and the molten metal in the throat passage is under suction. With the valve plunger so elevated to open the passage through the valve seat, lubricant from the reservoir and lubricant tube 38 may flow past the plunger seat 47 and into the throat passage. The amount of lubricant permitted to flow past the valve plunger and seat is therefore controlled by the distance and the interval of time during which the plunger is lifted off the seat, and lubricant cannot flow from the cup into the throat passage at any other time. The check valve 53 prevents molten metal from the throat passage from back-flowing upwardly into the tube. The check valve 53 and the oil plunger 45 are normally opened together and are closed at the same time. The nut 57 may be adjusted on the valve plunger so as to control the opening of the plunger and control the amount of oil permitted to enter the throat passage.

The structure and operation of the lubricating mechanism is more fully set out in my co-pending application, Serial No. 31,285, filed June 5, 1948, now Patent No. 2,540,523, issued February 6, 1951, and entitled Lubricating Mechanism for Strip Casting Machines.

A nozzle or tip member 75 is screw-threaded into the outer end of the outlet throat 21 from the crucible and has an axial flow passage therethrough for permitting the molten metal to flow outwardly through the nozzle. The extreme outer portion or tip of the nozzle is preferably substantially hemispherical in configuration, as clearly shown in Figure 5, and this hemispherical tip end of the nozzle is arranged to engage in a concave or frusto-conical opening formed in the entrant end of a die or mold 76 which determines the form of the strip of type metal to be produced by the machine. The die 76 may be any suitable type, but is preferably of the same structure as illustrated in my co-pending application, Serial No. 20,855, filed April 14, 1948, and includes an elongate longitudinal channel 77 into which the molten type metal flows and wherein such type metal is cooled and caused to set or solidify and be shaped before it passes from the exit end of the opening of the die to form the strip S of type metal.

The die 76 is releasably secured or clamped between a pair of cooling jackets 78 mounted in a coolant assembly frame 79 on the tabletop. The die 76 is laterally adjustable by the adjustment shown in detail in my application, Serial No. 20,855, filed April 14, 1948. The upper coolant jacket is movable vertically and is adjustable, by means of an elongate adjusting bolt or screw

80, toward and from the die or mold whereby the mold is securely releasably clamped in heat exchanging relationship between the two cooling jackets. Water is caused to circulate through the two cooling jackets, and the circulation of the water is controlled by means of a water valve 81 mounted on the front skirt of the machine and connected with a water pipe 82 which communicates with the cooling jacket.

An adjustable locking clamp 83 mounted on the jacket support engages the outer end of the die for pressing the die into leak-proof engagement with the nipple 75. The die or mold 76 is preferably positioned in such a manner that the strip is formed in a horizontal position with the printing edge thereof to one side, for a purpose which will be hereinafter more fully explained. Also the exit end of the die is adjustable laterally, whereby "bowing" or misalignment of the strip formed by the die may be corrected or eliminated.

The metal supplied to the die enters the die in molten form and is caused to solidify or set adjacent the outlet or exit end of the die channel 77, such solidification or setting being effected by the cooling jackets in heat exchanging relationship with the die through which cooling water is circulated for reducing the temperature of the type metal to cause it to set or solidify. A clutch and pulling mechanism 85 is mounted on the tabletop 45 near the exit end of the die for positively drawing the strip of type metal from the die. The pulling mechanism is operated intermittently, whereby the formed strip is pulled from the exit end of the die in short steps. Due to the cooling effect of the water jacket 78, the molten metal in the die channel 77 becomes mushy or semi-solidified during the period the metal is permitted to stand still in the die channel. This is particularly true of the narrow printing face of the strip. Consequently, when the pulling mechanism extracts a length of the solidified metal from the die, it is possible that a certain portion of the mushy semi-solidified type metal along the printing edge of the strip may be reduced in section and form a gap or notch in the printing edge, due to the lack of heat and fluidity necessary to permit the molten metal to refill the space occupied by the semi-molten mushy type metal. For overcoming and eliminating this defect, an auxiliary heater 84 is mounted on the tabletop and directs its flame toward the printing edge side of the die or mold 76, to normally maintain such portion of the molten metal in the die channel at a slightly higher temperature than the remainder thereof. Thus, when the pulling mechanism draws the strip from the die, the more molten portion of the type metal adjacent the printing edge will readily flow into the space occupied by the mushy semi-solidified portion of the metal and completely fill the same to provide a uniform smooth printing surface on the strip.

Referring now again to the pulling mechanism 85, it will be seen that the mechanism includes a base frame 86 having a pair of spaced shafts 87 extending transversely thereof and carrying sprocket wheels 88, which are positioned within the frame. A roller chain 89 is mounted on the sprocket wheels and alternate side links of the chain are provided with upwardly and outwardly extending flanges upon which foot or tread members 90 are secured. An adjustable upper frame 91 likewise has a pair of spaced shafts 92 mounted thereon carrying sprocket wheels 93 having a roller chain 94 extending between the sprocket

wheels and provided with foot pieces 95, identical with the foot pieces 90 of the previously described chain in the lower stationary base portion 86 of the pulling mechanism. The upper adjustable frame section 91 is slidable upon upright rods 96 carried by the lower frame member, and springs 97 are confined on the rods between the frames and normally urge the upper frame away from the lower frame. A cap plate 98 is secured on the upright rods 96 by means of nuts 99, and an adjusting screw 100 is threaded through this cap plate and engages against the upper cover 91a of the upper movable frame 91, whereby the adjusting screw may be operated to force the upper frame member downwardly toward the lower frame member or may be adjusted to permit the upper frame member to move upwardly away from the lower frame member.

The upper and lower frame members are so positioned that the two inside runs of the chains are parallel and coextensive, and the tread or foot members 90 and 95 are movable simultaneously to advance the strip of type metal S which extends between the two inside runs of the chain. The strip is clamped between the chains by adjusting the screw 100 to move the upper frame member downwardly until the lower run of the upper chain 94 firmly presses the strip between said lower run and the upper run of the lower chain 89. A guide bar 101 is removably mounted by means of bolts 102 on a cross piece 103 in the lower frame member between the sprocket wheels, and this guide bar engages the underside of the rollers of the upper run of the lower chain for supporting the chain against downward deflection. A similar downwardly facing pressure bar 104 is mounted by means of screws 105 on the underside of a cross member 106 located between the sprocket wheels of the movable upper frame, and said bar engages against the upper side of the rollers on the lower run of the upper chain 94 for pressing the same downwardly to prevent upward deflection of the chain.

45 A gear 107 mounted on one of the upper sprocket shafts 92 meshes with a gear 108 secured to one of the lower drive sprocket shafts 87, as clearly shown in Figure 7, whereby the two shafts are driven simultaneously, and the chains are therefore moved simultaneously.

50 For turning the shaft 87 on which the gear 108 is mounted, a ratchet mechanism 110 is provided. The ratchet mechanism may be any suitable type, but preferably consists of a sleeve 55 111 which is secured on the shaft by suitable pins and has a square external periphery, as clearly shown in Figure 8. A gear ring 112 having a circular bore 113 and gear teeth 114 on its periphery surrounds and is held in place on the 60 square sleeve 111 by a pair of flange rings 115 secured on opposite sides of the sleeve by bolts 116, and these flange rings engage on opposite sides of the gear ring whereby the gear is rotatable on the shaft about the square sleeve. The bore 113 of the gear ring is of such size that free cylindrical rollers 111 may be positioned within the bore of the gear ring and will ride free along the central portion of the outer plane surfaces of the square sleeve, but will wedge between the ring 65 and the plane surfaces of said sleeve to transfer movement from the gear ring to the sleeve when the gear ring is moved in a counter-clockwise direction in Figure 8, by means which will be hereinafter more fully described. The 70 bolts 116 which secure the flange rings to the

75 bolts 116 which secure the flange rings to the

square sleeve extend between the flange rings within the bore of the gear ring and are arranged to engage the cylindrical rollers 117 when the gear ring is moved in a clockwise direction, in Figure 8, and will permit the ring to travel in such clockwise direction without transferring movement from the ring to the square sleeve, since the rollers 117 may move in a clockwise direction with the ring only to the central portion of the plane surface of the square sleeve. The bolts 116 will prevent the rollers from moving past the central portion of the plane surfaces with the gear ring, whereby the gear ring may move freely with respect to the square sleeve, the flange ring and the rollers. It will be seen, therefore, that the gear ring 112, the rollers 117 and the square sleeve 111, provide for intermittent movement of the shaft 87 in a counter-clockwise direction, in Figure 8, and yet permit rotation of the gear ring in a clockwise direction without rotation of the square sleeve and the shaft 87.

For causing intermittent rotation of the gear ring 112 a rack gear 120, having teeth along one edge meshing with the teeth of the gear ring, is mounted on the upper end of an elongate rack shaft 121 which extends downwardly through the tabletop and has a roller 122 pivotally secured at its lower end. The roller 122 is disposed to be engaged by a cam 123 mounted on the main drive shaft 30 of the machine, whereby rotation of the drive shaft rotates the cam and causes intermittent lifting movement of the rack shaft and rack. The length of the stroke of the rack shaft and rack may be controlled by means of a lever arm 125 which is pivotally mounted in a hanger 126 beneath the tabletop and has a bifurcated end 127 which straddles the rack shaft 121 and is arranged to engage the lower end of the rack gear 120 which extends below the tabletop to limit downward movement of the rack gear. This lever arm is adjustable by means of an adjusting screw 128 which is threaded through the tabletop and engages the opposite end of the lever to adjust the position of the bifurcated end of such lever arm and thus adjust the length of travel of the rack gear. Thus, by adjusting the position of the bifurcated end of the lever arm, the downward travel of the rack gear 120 may be shortened or extended as desired, to control the length of stroke of the rack gear and thus the amount of turning imparted by the rack gear to the gear ring.

Due to the frictional engagement of the rollers of the chains 89 and 94 with the guide bars 101 and 104 and friction inherent in the other moving parts of the pulling mechanism, it will be seen that any undesired motion is substantially eliminated, and that the chains are moved only when the ratchet or clutch mechanism 110 positively causes rotation of the shaft 87. It will further be seen that the foot pieces 90 and 95 of the lower and upper chain of the gripping mechanism are constantly maintained in gripping engagement with the strip S of formed type metal at all times. There is no releasing of the grip on the strip of metal for moving a gripping mechanism for a new grip on the strip. The motion of the chain runs of the gripping mechanism is all in one direction, and the foot pieces engage over a substantial area of the strip, whereby deformation of the strip is substantially eliminated and the need for a brake to restrain the strip against being forced out of the die by the pump piston

23 during the interval between pulling movements is eliminated.

Also, since the gripping foot pieces of the chains of the pulling mechanism continuously grip the formed strip and hold the same, and since the chain is moved in only one direction, it will be seen that a uniform non-damaging pull is applied to the strip of formed metal. Also, since the gripping mechanism engages the strip on the long wide sides, rather than the printing edges, it will be seen that the printing face on the strip will not be damaged. Furthermore, since a plurality of the gripping foot pieces engage the strip over a large area or surface, it will be seen that the strip is not compressed or deformed by the gripping machine.

Also, it will be seen that the gripping or pulling mechanism may be moved into either gripping or non-gripping positions, as desired, simply by manipulation of the adjusting screw 100 to move the upper movable frame 91 downwardly or to permit the springs 97 to move such frame away from the strip. This permits quick access to the strip, and likewise permits adjustment of the gripping force applied to the strip. Furthermore, the length of stroke of the gear rack 120 may be readily controlled by means of the lever mechanism 125 to limit the amount of movement or rotation of the shaft 87 caused by the ratchet mechanism 110. Thus, an almost infinite variation in the length of pulling stroke applied to the strip by the pulling chains is readily obtainable. All parts of the pulling mechanism are readily accessible for replacement or repair, if needed.

The strip formed by the machine ejected at the outlet end of the pulling mechanism 85 will be a continuous strip and may be cut into sections of any desired length by any suitable means. However, for automatically cutting the strip into sections of predetermined desired lengths, as the strip is formed, it is preferred that the cutting mechanism 130 be provided. The cutting mechanism includes an upright frame member 131 which is secured by bolts 132 to the tabletop 15 of the machine. The upright frame member has a central opening 133 in which a movable cutter head 134 is slidable. The cutter head is carried by a rectangular frame 135 which is slidably supported upon laterally disposed outwardly extending rods or shafts 136 carried by the upright frame member 131. A stacking table or platform 137 is secured at one end by means of bolts 138 to the upright frame member and extends outwardly from the outer end of the tabletop. The extreme outer end of the stacking platform is supported by angularly disposed brackets 139 connected with the legs 16 of the machine and with the under side of the outer end of the platform.

Mounted within the movable frame 135 of the cutter head is a stationary knife blade 140 upon which the lower flat side of the strip S of formed type metal is arranged to slide. The cutter blade extends rearwardly through the central opening 133 of the upright frame member for guiding the movement of the movable head. A movable cutter blade 141 having an angular cutting edge at its lower end is secured to a movable yoke member 142 having a central opening formed therein through which the stationary blade 140 extends. The yoke is slidable vertically within the opening in the frame upon vertical guide rods 143, and is normally resiliently urged toward an elevated position by means of coiled springs 144 surrounding the guide rods and confined between the lower

end of the yoke and the lower cross piece of the frame.

An elongate trip rod 145 is connected by means of a pin 146 to the lower transverse portion of the yoke member and extends downwardly through an elongate slot 147 formed in the tabletop 15 and in the stacking platform. A striking washer or ring 148 is secured to the lower end of the trip rod by means of a nut 149, and a bell-crank lever 150 is pivotally secured on a hanger 151 below the tabletop and is arranged to strike the ring 148 to move the trip rod downwardly to cause the movable knife blade to move downwardly to shear the strip S extending between said movable blade and the stationary knife blade. The bell-crank member 150 has a roller wheel 152 at its lower end, and this roller wheel is arranged to be engaged by a cam 153 mounted on the main drive shaft 30 of the machine and rotated thereby to cause the bell-crank lever to be actuated to cause actuation of the trip shaft and the movable cutter blade.

The striking arm of the bell-crank lever is substantially Z-shaped in plan view and has a central portion 154 which extends longitudinally of the machine parallel to the pivot in the hanger 151. The extreme outer end or head 155 of the striking arm is turned outwardly toward the trip shaft, as clearly shown in Figures 9 and 10. This striking end of the bell-crank lever arm is normally spaced outwardly beyond the trip shaft, whereby the striking arm will not engage the striking ring on the trip shaft during its reciprocating movements caused by the actuation of the bell-crank lever by the cam. However, when the movable cutter head 134 and the trip shaft carried thereby are moved longitudinally to the right, as will be hereinafter explained, the striking ring is moved beneath the striking head of the bell-crank lever, and the striking head will engage the ring to move the trip shaft downwardly and thus move the cutter blade downwardly to shearing position.

Helical coiled springs 156 are mounted on the slide rods 136 for normally urging the cutter head 134 inwardly toward the upright frame member 131. However, the springs may be provided at any other suitable location for urging the cutter head toward the upright.

An elongate slide rod 158 has one end secured in the movable frame 135 and its other end slideable in an upright supporting bracket 159 carried near the outer end of the stacking platform. An adjustable stop member 160 is slideable on the rod 158 between the frame and bracket and may be secured in various positions on said rod by means of a set screw 161. The stop member extends downwardly from the slide rod and is so disposed as to be engaged by the advancing end of the strip S of formed metal, whereby the strip will act through the stop member to push the slide rod outwardly and thus pull the cutter head 134 outwardly with the strip. When the cutter has been moved in this manner sufficiently to the right or outwardly to permit the striker head 155 of the bell-crank lever to engage the striking ring 148 on the trip shaft 145, the movable cutter blade will be moved downwardly to shear the desired length of strip from the main body thereof. Thus, the cutter head moves with the strip and the strip is, therefore, stationary relative to the cutter head during the cutting operation.

When the strip has been so sheared, it no longer exerts its force against the stop member and the springs 156 will pull against the cutter head to return the same to the original position.

abutting against the upright frame member 131. When the cutter head has thus returned to its initial position, the striking ring at the lower end of the trip shaft is moved out of alignment with the striking head of the bell-crank lever and the movable cutter is therefore stationary and not actuated.

An elongate support rod 165 is slung by means of angular bracket members 166 below the slide rod 158, and is so positioned that the formed strip S will slide along such support rod. The support rod likewise extends through an opening formed in the lower end of the stop member 160 for further supporting the support rod and insuring that the stop member is so positioned that it will be engaged by the advancing strip of type metal.

The strip S travels along the support rod in a horizontal position, as clearly shown in Figures 9 and 10, and the support rod is positioned slightly to the rear of the axis of the strip, nearer the printing face of such strip. When the desired length of the strip has been severed by the cutter head, the severed portion will fall and, due to the engagement of the support rod with the rear portion of the strip on which the printing face is formed, the strip will pivot on the support rod and fall toward and on the stacking table or platform with the printing face upward. This eliminates damage to the printing face of the formed strip.

A suitable reciprocating bar 170 is slideable laterally on the upper surface of the stacking platform and moves the severed sections of the formed strip toward the front side of such platform. The pressure bar is moved by means of actuating arms 171 adjustably mounted on a shaft 172 carried by brackets 173 on the under side of the stacking table. An elongate lever arm 174 is also secured on the shaft 172 and has a roller 175 at its lower end which is arranged to be engaged by a cam 176 carried on the outer end of the main drive shaft 30 of the machine. Thus, as the drive shaft is rotated, the cam engages the roller on the lever arm to swing the actuating arms and thus cause the pressure bar to be reciprocated on the surface of the stacking table. A retainer bar 180 is pivotally mounted at its center on an elongate resilient pressure arm 181 which is pivoted on a pin 182 near the outer forward end of the stacking table and maintains pressure on the forward group of severed strips for maintaining the strips in upright stacked position on the table.

From the foregoing, it will be seen that an improved strip casting machine has been provided which has incorporated therein an improved mold or die for forming the strip, an improved cooling apparatus for cooling the die, improved drawing and holding means, and an improved cut-off and stacking mechanism, whereby printer's leads, slugs and rules may be formed rapidly and automatically after the machine has been initially started and adjusted. It will particularly be noted that the strip of formed metal is drawn from the mold or die in a horizontal position and travels in such horizontal position until the desired length is cut off from the advancing strip and stacked with the printing face upwardly on the stack table of the machine, thus preventing damage to the printing face of the strip. It will further be seen that the gripping mechanism continuously grips the formed strip and holds the same, said mechanism being intermittently moved to cause the strip to be drawn.

through the die of the machine. Also, the gripping mechanism engages the formed strip over a large area to reduce the application of pressure per unit of area at any given point on the strip whereby damage or deformation of the strip by the gripping mechanism is eliminated. Furthermore, an improved ratchet mechanism for causing intermittent movement of the pulling mechanism has been provided, which permits adjustment of the amount of movement of the strip through an infinite number of increments of distance within the capacity of the machine. Likewise, an improved lubricating mechanism has been provided in the machine.

It is also important to note that means has been provided for controlling and maintaining the temperature of the metal passing through the die channel of the die at the proper temperature to prevent the formation of pits or irregularities in the printing face of the strip formed by the die.

It is believed manifest that all operating parts of the machine are quickly and readily adjustable and are easily accessible for detachment and replacement to facilitate the repair or adjustment of the machine.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. A holding and pulling mechanism for a strip casting machine and including, a stationary frame, a movable frame positioned above the stationary frame and normally resiliently urged away from said stationary frame, a pair of spaced sprocket wheels in said stationary frame, an endless roller chain having foot pieces mounted thereon movably carried by the sprocket wheels with the foot pieces projecting above the upper end of the frame, a pair of spaced sprockets in the movable frame, an endless roller chain mounted on said movable frame sprockets and having foot pieces thereon projecting below the lower end of said frame, an adjusting member engaging the upper movable frame for moving said upper frame toward the stationary frame to move the exposed portion of the upper chain into gripping relationship with the exposed portion of the lower chain for engaging and positively gripping a strip of solidified metal to hold and to move the same, and a drive member connected with one of the sprockets of the lower frame for intermittently moving the same in only one direction.

2. A holding and pulling mechanism of the character set forth in claim 1 wherein, the lower frame is provided with a guide bar engaging the rollers of the chain beneath the upper exposed portion of the endless chain for supporting the same against downward deflection, and the upper movable frame is provided with a guide bar engaging against the upper side of the rollers of the lower exposed portion of the upper chain for preventing upward deflection thereof.

3. A strip holding and pulling mechanism for a strip casting machine including, a lower stationary frame, spaced shafts disposed parallel to each other in said stationary frame, sprocket wheels carried by said shafts, an endless roller chain carried by said sprocket wheels, foot pieces carried by alternate links of the roller

chain, the upper run of said chain being exposed above the upper end of the frame, a guide bar disposed below and engaging against the rollers of the upper run of the chain, an upper movable frame, guide means carried by the lower frame and engaging the upper frame for guiding the vertical movement of the upper frame with respect to the stationary frame, spring means interposed between the stationary frame and the movable frame normally urging the movable frame away from the stationary frame, an adjusting member engaging the movable frame for adjustably moving the movable frame toward the stationary frame and holding said movable frame in various adjusted positions with respect to said stationary frame, a pair of spaced shafts carried by said movable frame and disposed parallel to each other, sprocket wheels carried by said movable frame shafts, an endless roller chain mounted on said movable frame sprockets, foot pieces carried by alternate links of said movable frame chain, the lower run of said movable frame chain being exposed below the lower edge of said movable frame, a guide bar carried by said movable frame above and engaging against the lower run of said movable frame chain, means operatively connecting one of the shafts of the movable frame with one of the shafts of the stationary frame whereby the roller chains are moved simultaneously, and means for rotating one of said shafts intermittently in a single direction.

4. A holding and pulling mechanism of the character set forth in claim 3 wherein the means for intermittently moving one of the shafts in one direction includes, a driven member on said one shaft of the pulling mechanism, a reciprocating drive member, clutch means interposed between said reciprocating drive member and the driven member for intermittently moving the driven member in a single direction, and means for varying the arc through which the driven member is turned.

5. A strip casting machine including: a frame; a drive shaft carried by the frame; a melting pot on the frame having an outlet nozzle; a pump in the melting pot having a driving connection with the drive shaft for intermittently forcing molten metal through the outlet nozzle; a die having a strip forming channel therethrough with an inlet and an outlet at opposite ends thereof; a pivotal sealing connection between the inlet of the die and the outlet nozzle of the melting pot whereby molten metal from the melting pot is directed into the channel in the die; adjustable clamping means on the frame releasably maintaining the inlet end of the die in pivotal sealing engagement with the outlet nozzle, said clamping means also providing, for adjustment of the outlet end of the die pivotally about the outlet nozzle connection in the plane of the major cross-sectional dimension of the die channel, whereby bowing of the strip formed may be corrected while the machine is operating; cooling members carried by the frame spaced from the outlet nozzle and adapted to releasably clamp the die therebetween in heat exchanging relationship therewith at such adjusted positions for cooling and solidifying the metal passing through the die channel; a gripping and pulling mechanism on the frame spaced from the outlet end of the die and adjustable into and out of positive gripping and pulling engagement with the strip formed by the die, said gripping and pulling mechanism having a driv-

ing connection with the drive shaft for moving said gripping and pulling mechanism intermittently in only one direction in timed relation with the melting pot pump for drawing the solidified strip from the die.

6. A strip casting machine including, a crucible having an outlet, a die having a strip-forming channel therethrough and having its inlet end in pivotal sealing engagement with the outlet from the crucible for receiving molten metal therefrom, adjustable clamping means engaging the die releasably maintaining the die in engagement with and for shifting the outlet end of the die about such pivotal engagement with the crucible outlet, said clamping means being adjustable during the operation of the machine, cooling chamber members releasably maintained in heat-exchanging engagement with the die for cooling and solidifying the metal passing through the die channel, the die being adjustable between the cooling chamber members about its pivotal sealing engagement with the crucible outlet, and a gripping and pulling mechanism adjustable into and out of engagement with the solidified strip projecting from the outer end of the die for positively gripping the same and movable intermittently in only one direction while so gripping the strip for drawing the solidified bar from the die, the adjustable mounting of the die with respect to the crucible outlet and the cooling chamber members providing for forming a straight solidified bar.

7. A holding and pulling mechanism for a strip casting machine having a melting pot, a die connected at one end with said melting pot to receive molten metal therefrom and means for cooling the die whereby the metal is caused to solidify into a strip as it passes therethrough, said holding and pulling mechanism comprising:

a pair of endless chains having foot pieces mounted thereon, sprockets for supporting said chains, the sprockets for one chain rotating about axes fixed with respect to the melting pot, the sprockets for the other chain being mounted in a frame adjustable toward and away from said axes whereby said other chain is movable into and out of positive gripping engagement with the strip of solidified metal and whereby the strip is positively gripped and held between the chains on opposite sides and the gripping engagement of the foot pieces with the strip may be adjusted and controlled, and drive gears connected with the chains for intermittently moving said chains in only direction to draw the solidified metal strip from the die, said chain foot pieces holding the strip against movement during the intervals between driving movements.
